UNITED STATES PATENT OFFICE

2,222,719

AIR BLAST CIRCUIT BREAKER

David C. Prince, Swarthmore, Pa., assignor to
 General Electric Company, a corporation of
 New York

Application July 8, 1939, Serial No. 283,386

6 Claims. (Cl. 200—148)

My invention relates to electric circuit breakers, and more particularly to circuit breakers of the fluid-blast type having application to circuits in high voltage transmission systems that are characterized by high rates of increase of recovery voltage across the breaker terminals, and has for its principal object the provision of an improved fluid-blast circuit breaker having increased interrupting capacity.

10 It has been found that the interrupting capacity of a circuit breaker in a high voltage circuit depends to a great extent on the circuit characteristics relating to the rate of increase of recovery voltage when the current is interrupted. Although the breaker may be successful in interrupting the current momentarily, the recovery voltage across the interrupting gap may rapidly rise to such a value that arcing is re-established before the breaker has sufficiently 15 increased the dielectric strength of said gap. By way of example, in a certain instance, a gas blast circuit breaker interrupted 15,000 amperes in a 13.2 kv. circuit having a recovery rate of 330 volts/microsecond. However, when the recovery 20 rate was increased to 1500 volts/microsecond, the same breaker was successful in interrupting but 5,000 amperes under otherwise similar conditions. For interrupting higher current under such conditions, it would be necessary greatly 25 to increase the pressure and the intensity of the gas blast or, if it is impractical to increase the gas pressure, the size of the blast passage in which the arc is interrupted could be enlarged to provide for greater gas volume. However, 30 such changes would result in either a more expensive or larger breaker.

In accordance with my invention, the interrupting capacity of the circuit breaker for a given blast pressure and gas consumption is greatly 35 increased by inserting a suitable resistance in the circuit at a break subject to an effective gas blast, thereby decreasing the voltage recovery rate of the circuit, and subsequently interrupting the greatly decreased current at a much 40 more favorable recovery rate by a comparatively limited blast at another break in series with said first break.

My invention will be more fully set forth in the following description referring to the accompanying drawing, and the features of novelty which characterize my invention will be pointed out with particularity in the claims annexed to and forming a part of this specification.

Referring to the drawing the single figure thereof is an elevational view partly in section

of an electric circuit breaker of the gas blast type embodying the present invention.

The gas blast circuit breaker illustrated by way of example comprises relatively movable contact structure arranged to form two breaks in series at 1 and 2 respectively upon opening of the circuit. The contact structure specifically shown comprises a pair of fixed contacts 3 and 4 which coact with movable contact members 5 and 6. The movable contacts 5 and 10 6 are electrically interconnected as by a stationary terminal bridging structure 7 and suitable current transfer contacts 7'. For the purpose of operating the contacts 5 and 6 in unison, they are connected to an insulating member or bar 8 15 in turn operatively connected to suitable actuating mechanism (not shown). It will be apparent from the above description that opening and closing of the circuit at the points 1 and 2 can be accomplished by reciprocal operation of 20 the contact structure 8.

For the purpose of insulating the terminal contacts 3 and 4 and of forming a passage for directing gas under pressure to the aforesaid breaks, an insulating housing 9 is mounted on 25 the terminal structure 7 for supporting the terminal contacts 3 and 4 in spaced relation thereto. The housing 9 forms two vertically positioned branches 10 and 11 interconnected by a transverse passage 12 that is in turn connected 30 at 13 to a suitable source of gas pressure. The contact members 5 and 6 can, if desired, be made substantially fluid-tight with respect to the lower part of the housing or bridging terminal 7, and the terminal contacts 3 and 4 fitted 35 as cover members for the vertical extensions 10 and 11 of the housing so that in the closed contact position shown, the housing 9 is for practical purposes substantially gas-tight.

To this end, the stationary contacts are of 40 the nozzle type so that the movable contact members close the nozzle in the closed circuit position. In the arrangement shown, the nozzle opening of the contact 3 is appreciably more restricted in cross-section than the opening of the contact 4 for a purpose hereinafter described. In order to compensate for the current carrying capacity of the contact 5 by reason of the comparatively small contact tip 5', auxiliary contacts 5" carried by the member 5 are arranged 45 to contact with the terminal 3 in parallel with the contact tip 5'.

For the purpose of facilitating the interruption of a high voltage power circuit characterized by a high recovery voltage rate, a resistor

14, the resistance of which depends on the characteristics of the circuit to be controlled, is connected in shunt with the break at 2. As shown, the resistor 14 is electrically connected at 15 to the terminal contact 4 and at 16 to the bridging terminal 7. Accordingly, when the contact 6 breaks contact with 4, the resistance at 14 will be connected across the gap so formed.

The operation of the circuit breaker is as follows. Assuming the breaker to be in closed circuit position shown, the circuit between the line terminals at 17 and 18 is completed through contacts 3-5, bridging conductor 7 and contacts 6-4. Lowering of the contact bar 8 coincident with admission of gas under pressure to the housing 9 by way of conduit 13 causes initial separation of the contacts 4 and 6 together with a gas blast through the stationary contact opening 4'. An effective arc interrupting blast 20 at the proper blast pressure takes place when the contacts are separated but a short distance, such as approximately two centimeters. At this point, the contact 5 is still in engagement by reason of the longer extension tip 5' so that the 25 arc is confined to the gas blast between contacts 4 and 6. At a current zero, the arc is interrupted and the resistance 14 automatically inserted in the circuit. The high velocity gas blast now prevents reestablishing of the arc. 30 The line current and also the voltage recovery rate are thereby greatly reduced by the resistance so that upon separation of the contacts 3 and 5 immediately thereafter, the greatly reduced gas blast at the nozzle opening of the 35 contact 3 is quite sufficient to extinguish the low current arc. This second interruption completely opens the circuit with a minimum expenditure of gas blast energy. The breaker can be comparatively compact in design since large 40 blast openings and contact structures are not required for high current interruptions.

Although sequential operation of the contacts at the two breaks is preferred, such operation is not entirely essential as the breaks may be 45 formed simultaneously.

The control of the gas blast by suitable valve means forms no part of the present invention and is omitted in the interest of clearness. It will be apparent however that such control may 50 be in response to the usual relay operation or in accordance with the movement of the contacts as desired.

It should be understood that my invention is not limited to specific details of construction and 55 arrangement thereof herein illustrated, and that changes and modifications may occur to one skilled in the art without departing from the spirit of my invention.

What I claim as new and desire to secure by 60 Letters Patent of the United States is:

1. An electric circuit breaker comprising relatively movable contact structure arranged to form a plurality of breaks in series, a resistance connected in shunt with one of said breaks, means for initially opening the circuit at said resistance shunted break, means for directing a fluid blast through said resistance shunted break to interrupt arcing thereat, and means for directing a second comparatively restricted fluid blast through another series break for finally interrupting the circuit.

2. An electric circuit breaker comprising rela-

tively movable contact structure arranged to form a plurality of breaks in series, at least two of said breaks being formed in fluid passages, a resistance connected in shunt with one of said breaks, means for initially opening the circuit at said resistance shunted break, means for directing a fluid blast through the passage at said resistance shunted break to interrupt arcing thereat, and means for directing a second fluid blast of appreciably lower intensity through the 10 passage at the subsequently formed series break for finally interrupting the circuit.

3. An electric circuit breaker comprising relatively movable contact structure arranged to form a plurality of breaks in series, at least two 15 of said breaks being formed adjacent to the exhaust portions of separate fluid passages, a resistance connected in shunt with one of said breaks, means for initially opening the circuit at said resistance shunted break, means for directing a fluid blast through the passage at said resistance shunted break to interrupt arcing thereat, and means for directing a comparatively restricted second fluid blast through the 20 passage at the subsequently formed series break for 25 finally interrupting the circuit.

4. An electric circuit breaker of the gas blast type comprising a pair of fixed contacts and coacting movable contact members arranged to form two breaks in series, a resistance connected 30 in shunt with one of said breaks, means for directing a gas blast through the arc formed at said resistance shunted break for inserting said resistance in the circuit, and means for directing a gas blast of less magnitude through the other 35 break for finally interrupting the circuit.

5. An electric circuit breaker of the gas blast type comprising a pair of fixed contact structures forming two separate gas blast passages, one of which is restricted in cross-sectional area 40 as compared with the other, coacting movable contacts normally closing said passages in the closed circuit position and arranged to form with said fixed contacts two breaks in series, one of said movable contacts being adapted to separate 45 in advance of the other movable contact, a resistance connected in shunt with the break thus initially formed for reducing the rate of increase of recovery voltage of the circuit, and means for directing a gas under pressure to said passages 50 for interrupting arcing at said initially formed break and thereby causing insertion of said resistance in the circuit, said gas under pressure subsequently interrupting the circuit at said restricted passage.

6. Electric circuit interrupting means of the gas blast type comprising a pair of relatively movable contacts, means forming a gas passage in which said contacts separate, means for directing a gas blast of sufficient magnitude 60 through said passage to interrupt a high current power arc upon separation of said contacts, a resistance connected in shunt with said contacts for reducing the line current upon interruption of said arc, a second pair of contacts connected in series with said first-named pair, means forming a second gas passage in which said contacts separate, and means for limiting the magnitude of the gas blast at said second passage as compared with said first passage for interrupting 65 the aforesaid reduced line current.

DAVID C. PRINCE.
